UNITED STATES PATENT OFFICE.

STEPHEN J. HEINRICH, OF NEWTON HIGHLANDS, MASSACHUSETTS.

AIR-BRUSH.

1,272,438.

Specification of Letters Patent. Patented July 16, 1918.

Application filed March 13, 1917. Serial No. 154,572.

To all whom it may concern:

Be it known that I, STEPHEN J. HEINRICH, a subject of Austria-Hungary, residing at Newton Highlands, in the county of Middlesex, State of Massachusetts, have invented an Improvement in Air-Brushes, of which the following is a specification.

This invention relates to air brushes or paint sprayers, and is embodied in a device 10 of the concentric jet type adapted to project a cone-shaped spray by forcing a current of air through an orifice surrounding a liquid delivery orifice.

My device is primarily designed and intended for delivering heavy, viscous materials, such for instance as cellulose solutions, which have very volatile solvents and which rapidly evaporate and cause a hardening of the material on and consequent clogging of 20 the working parts of the device.

Air brushes used with such quick drying solutions become quickly clogged after use if the solution is permitted to remain in the liquid orifice and associated parts and, as 25 heretofore constructed, must be completely dismantled in order to obtain access to the small liquid and air orifices to enable a wire or other cleaning tool to be inserted therein to remove the solidified matter and to permit 30 that part of the brush bearing the nozzles to be immersed in a cleaning solution.

Such a complete dismantling of the brush consumes an inordinate amount of time. Moreover, after being reassembled, it is necessary to readjust the brush for the proper 35 amount of air and liquid flow, which is a matter of considerable difficulty.

An object of my invention is in the provision of an air brush in which the parts 40 liable to become clogged may be easily and quickly removed from the main body of the brush for cleaning purposes, and thereafter again with facility replaced in their former position.

45 A further object of the invention is in the provision of such a brush in which the removal of the above named parts does not affect the initial adjustment of the air and liquid nozzles and in which, upon the re-

placement of the detailed part or parts, the 50 brush will be again conditioned in its original adjustment.

The means whereby I accomplish these objects of my invention is in the detachable arrangement of the brush body, or frame, 55 bearing the air and liquid nozzles, with the main body or standard of the brush, whereby, upon the loosening of a set screw, the brush body may be removed for cleaning or other purposes. The liquid flow adjusting 60 rod may be secured to the main body of the brush, and as its adjustment is not disturbed by the detaching of the brush body, the adjustment of the liquid flow is in no way altered or changed during such detachment. 65

Another object of the invention is the provision of means for adjusting the regulating means by which the maximum volume of material issuing from the delivery orifice may be determined, and the provision of 70 other means of adjustment, whereby the volume of material issuing from the delivery orifice, less than maximum, may be variably controlled.

Figure 1 is a side elevation of an air brush 75 embodying this invention.

Fig. 2 is a longitudinal vertical section of the same.

Ten (10) indicates any suitable receptacle adapted to contain the liquid to be sprayed, 80 and 12 its cover. Thirteen (13) represents a standard erected on the cover 12, adapted to support the operating parts. Said standard is or may be hollow, and in open communication with the receptacle, particularly for 85 cheapness in manufacture.

Said standard has rigidly secured to its upper end a support for the frame bearing the spraying nozzles. Said support will now be described. Fifteen (15) represents a barrel or outer tube, which is horizontally arranged, and has its connection with the standard, intermediate its length. Said outer tube has concentrically arranged within it an inner tube 16, which extends throughout 90 its length, and preferably projects therefrom at its front end. Said inner tube has concentrically arranged within it a regulat- 95

ing valve-rod 17. These three elements are adapted to be held in fixed relation to each other, although the rod 17 is adapted to be adjusted longitudinally. The outer tube 15 has an internal boss 18, with a center-hole through it to snugly fit the inner tube 16, and said boss projects from the outer tube at the under side to fit the opening in the top of the standard, thus closing said opening 10 and attaching the outer tube to the standard.

As here shown, a cylindrical hollow head 19 is provided, and one end of the outer tube 15 is extended over the end of said head for a short distance, and the corresponding end 15 of the inner tube 16 is screwed into a recess in the head, and the valve-rod 17 is screwed into or otherwise fixedly connected with the end of the head, all as illustrated in Fig. 2. By rotating the head its threaded recess will 20 turn on the end of the inner tube, and the outer tube will slide freely along on the outside of the head, and the valve-rod will be moved longitudinally in a direction according to the direction of rotation of the head.

25 The valve-rod 17 has arranged on it, at an intermediate point, a cylindrical block 20, which snugly fits the interior of the inner tube, thus supporting said rod at such point, and said block may be arranged to slide in 30 said inner tube when the rod is adjusted longitudinally.

Twenty-five (25) represents a cylindrical liquid delivery tube, which extends upward from the interior of the receptacle through 35 the standard 13, and the walls of the outer and inner tubes, terminating at the interior of the inner tube, so that the interior of the inner tube is in open communication with the receptacle, and the liquid material contained in the receptacle is free to pass to the interior of said inner tube.

The movable frame brush body bearing the spraying nozzle is adapted for sliding and detachable engagement with the aforesaid 45 support, and said movable frame will now be described.

Thirty (30) represents a tubular portion adapted for sliding engagement with the outer tube 15, of the support, it being arranged 50 on the end-portion of said outer tube and movable longitudinally relative thereto, and its longitudinal movement is limited by a screw 31, extended through a boss 32, on said tubular portion and into or through a slot 33, formed in the wall of the outer tube. Said tubular portion has at its forward end a hollow conical nozzle 35. Said tubular member also has arranged within it a cylindrical block 36, at a point intermediate its 55 length, which serves as a support for it and for the inner tubular member to be described, which block has a passage 37, through it for the air, and said block is or may be connected or formed integral

with a frame portion 38, which extends 65 downward from the tubular member, and said portion 38 has an air passage 39, in continuation of the air passage 37, which leads to a valve-controlled passage, and to a recess 40, and said portion 38 has a nipple 70 41, adapted for connection with an air supply pipe, flexible, if desired, and has an air passage through it in open communication with said recess 40. Thus the air may pass through the nipple and recess and valve-controlled passage, and the passages 39, 37, to the interior of the outer tubular member of the support and to the hollow conical nozzle 35.

Forty-five (45) represents a valve which 80 is provided for controlling the air passage. It is arranged in the recess 40, and has stems 46, 47, extended, respectively, in opposite ways from it. The stem 46 extends outward through the portion 38, and has a head 49, 85 adapted to be engaged by a finger, to move the valve in one direction; and the stem 47 extends rearward into a recess 50, formed in a bearing member 51; and a spring 52 is arranged on said stem 47, between the 90 valve proper and the bearing member, the tendency of which is to expand and normally hold the valve in closed position, so that the air passage is normally closed. As an additional sliding support for the movable frame the bearing member 51 may be 95 made to project rearward, and enter a correspondingly shaped socket 55, in a guiding-member 56, supported upon the standard.

The movable frame has an inner tubular 100 member 60, arranged concentrically to the outer tubular member and adapted for sliding engagement with the inner tube 16, it being fitted on the end-portion thereof, and said inner tubular member has at its outer 105 end a hollow conical nozzle 61, for the liquid, which is arranged within the conical nozzle 35, and so related thereto that a circular air orifice is provided between said nozzles, at their outer ends, so that the air which is 110 forcibly projected from said orifice will draw the liquid through the delivery orifice of the conical nozzle 61. Said conical nozzle 61 is screwed onto the end-portion of the inner tubular member and against a circular plate 62, which latter is arranged between the end of the outer tubular member and a shoulder on the interior of the conical nozzle 35. A needle-valve 70, which serves as a regulating valve for the liquid delivery 115 orifice is formed on the valve-rod 17, and is adjustable therewith for the purpose of controlling the volume of liquid material which is delivered from the liquid orifice by a movement toward and from said orifice. 120 The plate 62 has a hole 63 through it to admit of the passage of air.

The movable frame, as a whole, is spring

controlled, and, as here shown, a spring 75 is arranged between the inner and outer tubes, one end bearing against the block 36, and the other end against the boss 18, and the tendency of said spring is to expand and thrust the movable part in an outward direction, which movement is limited by the screw 31 engaging the forward end of the slot 33. Movement of said frame in the other direction is limited by the screw 31 engaging the other end of the slot.

By the construction above described, in which all connections between the movable frame or brush body and the brush support are by sliding joints and the frame is secured to the support only by the set screw 31, it may be seen that, by the simple unloosening of said set screw, whereby its lower end is withdrawn from engagement with the slot 33 in the support, the movable frame or brush body may be detached from the support. As said frame or brush support bears both the air and liquid nozzles, it is a simple matter to immerse it in a cleaning solution to dissolve the solidified spraying material or to permit a cleaning tool to be passed through the liquid orifice. The movable frame or brush body may be again secured to the brush support by merely 30 sliding the frame or brush body over the support and tightening the set screw, whereupon the brush is again conditioned for operation.

The removal of the movable frame or brush body from its support and its replacement thereon does not affect the initial adjustment of the flow of liquid from the brush because, as the liquid regulating valve, or rod 17 is secured to the brush support, its adjustment is in no way affected by the detachment of the movable frame or brush body, and when said frame or brush body is replaced in engagement with the support, the liquid orifice 61 and the valve portion 45 of the rod 17 again resume their former relative positions.

The arrangement of the parts of the air brush, in which the liquid orifice is normally open to its maximum extent is an advantage in that there is but little liability of the orifice and needle valve becoming stuck together by the spraying liquid as it dries in the brush, because of the comparatively great distance between the needle valve and the inner wall of the liquid nozzle, as is the case with brushes in which the needle valve is normally set for a minimum liquid discharge, and in which the needle valve, in consequence, is almost touching the inner 60 wall of the liquid nozzle.

One way of operating the device is as follows:

The device may be grasped by the hand, the middle finger resting on the head 46

of the air-controlled valve. The rear tubular portions resting between the thumb and forefinger with the guide 56 resting against the palm, and the forefinger engaging a finger rest 80. Assuming the receptacle to contain liquid to be sprayed and the air passage connected with a source of supply by pressing the middle finger, the air valve may be opened more or less according to the volume of air desired. If the area to be covered by the spray, or less material is required, a pull upon the lever 80 with the forefinger is the result, with the part being moved as a unit, so that the needle valve 70 more or less closes the liquid orifice, for it will be understood that as the needle approaches the liquid orifice the volume of liquid delivered is less, the decreasing amount being gradual as the movable part, including the liquid orifice, is moved relative to the needle. When a large number of articles of certain dimensions are to be sprayed, the needle will be adjusted by the head 18, so that the movable part may be moved rearward its full distance, or until the screw engages the end of the slot which, of course, is an easy matter for moving said parts, but it will be understood that at any moment more liquid may be delivered by permitting said movable part to move forward from its rearmost position. 95

I claim:

1. In an air brush, a frame bearing air and liquid spraying nozzles, a support for said frame, a regulating valve on said support and extended into said spraying nozzles, 100 said frame being movably related to its support whereby the spraying nozzles are movable toward and from the regulating valve.

2. In an air brush, a frame bearing air and liquid spraying nozzles, a support for said frame, a regulating valve on said support and extended into said spraying nozzles, and adjusting means for said valve, said frame being movably related to its support whereby the spraying nozzles are movable 110 toward and from the regulating valve. 105

3. In an air brush, a frame bearing the spraying nozzles arranged for connection with an air supply, a support for said frame arranged for connection with a liquid supply, a regulating valve on said support and extended into said spraying nozzles, said frame being movable on the support to vary the position of the spraying nozzles with respect to the regulating valve. 115

4. In an air brush, a frame bearing the spraying nozzles arranged for connection with an air supply, a support for said frame arranged for connection with a liquid supply, a regulating valve arranged on the support and extending into said spraying nozzles, and adjusting means therefor, said frame being movably related to its support 120 125

- whereby its spraying nozzles are movable toward and from the regulating valve to vary the discharge of liquid from the brush.
5. In an air brush, a support arranged for connection with a liquid supply, a frame bearing the spraying nozzles and arranged for connection with an air supply, and a needle rod on said support which projects therefrom, the needle of which is arranged adjacent the spraying nozzles, said frame bearing the spraying nozzles being movably arranged on its support to vary the position of the nozzles with respect to the needle rod.
6. In an air brush, a support arranged for connection with a liquid supply, a movable frame bearing the spraying nozzles and arranged for slidable movement with said support to vary the discharge of liquid from the brush and for connection with an air supply, and a needle rod arranged on said support which projects forward, its needle being arranged adjacent the spraying nozzles.
7. In an air brush, a frame bearing the spraying nozzles, a support for said frame, a needle rod on said support having its needle arranged adjacent the spraying nozzles, and adjusting-means for said rod, said frame being movably related to its support whereby the spraying nozzles are movable toward and from the needle rod to vary the discharge of liquid from the brush.
8. In an air brush, a frame bearing the spraying nozzles, a support for said frame, said frame being movably related to said support, an expansive spring arranged between said frame and its support, and means arranged on the frame adapted for manual engagement by which said frame may be moved against the force of said spring, and a regulating valve on the support with respect to which the spraying nozzles are moved by the frame.
9. In an air brush, a frame bearing the spraying nozzles arranged for connection with an air supply, a support for said frame arranged for connection with a liquid supply, a regulating valve on said support, said frame being movable on the support to vary the position of the regulating valve with respect to the spraying nozzles, and its joint connection with the support being arranged in front of the liquid inlet, whereby the liquid material will engage the joint-connection.
10. In an air brush, a support arranged for connection with a liquid supply, a frame bearing the spraying nozzles, and arranged for connection with an air supply, said frame being removably mounted on said support, and a regulating valve on said support which projects therefrom, and has its needle adapted to be arranged adjacent the spraying nozzles.
11. In an air brush, a support arranged 65 for connection with a liquid supply, a frame bearing the spraying nozzles and arranged for connection with an air supply, said frame being removably mounted on said support and adapted for sliding engagement therewith, and a regulating valve on said support which projects therefrom and has its needle adapted to be arranged adjacent the spraying nozzles.
12. In an air brush, a frame bearing the 75 spraying nozzles having a tubular portion, a support for said frame comprising two concentrically disposed tubes, the outer tube being adapted to receive upon it the tubular portion of the frame, an adjustable head 80 on the rear ends of said tubes, a needle rod arranged in the inner tube and secured to said head, the needle of which is arranged adjacent the spraying nozzles, said frame being movable with relation to its support 85 to move the spraying nozzles toward and from the needle rod.
13. In an air brush, a frame bearing the spraying nozzles, a support therefor, a liquid regulating valve arranged on the support, 90 said frame having a downwardly-extended portion with an air passage throughout its length, and adapted for connection with an air supply, and a spring-controlled controlling-valve arranged in said air passage having a laterally extended engaging-head by which to operate it.
14. In an air brush, a frame bearing the spraying nozzles, a support therefor, a standard bearing said support, a liquid 100 valve arranged on said support, said frame having a downwardly-extended portion with an air passage throughout its length and adapted for connection with an air supply, and having a rearward bearing portion arranged for engagement with a bearing portion on the standard, a controlling-valve for the air passage arranged on said downwardly-extended portion, having a head arranged to be engaged by the finger when 110 said downwardly-extended portion and standard are grasped by the hand, thereby to control the supply of air.
15. In an air brush, a frame bearing the spraying nozzles, a support for said frame, 115 a liquid regulating valve on said support, said frame arranged to be removably connected with said support.
16. In an air brush, a frame bearing the spraying nozzles, a support for said frame, 120 a liquid regulating valve on said support, said frame arranged to be removably connected with said support.
17. In an air brush, a liquid nozzle, an air nozzle in normally fixed adjustment 125 with the liquid nozzle, a support for said nozzles, a liquid regulating valve on said support, said nozzles being arranged to be

removed to adjust said liquid nozzle with respect to the regulating valve to vary the flow of liquid therethrough.

18. In an air brush, a liquid nozzle, an air nozzle, a support for said nozzles, and a liquid regulating valve on said support, said liquid nozzle being arranged to be moved with respect to said valve to vary the flow of liquid from said nozzle and nor-

mally adjusted away from said valve for the maximum liquid flow.

In testimony whereof, I have signed my name to this specification, in the presence of two subscribing witnesses.
